UNITED STATES PATENT OFFICE.

WILLIAM F. NORMAN, OF NEVADA, MISSOURI.

COLLAPSIBLE METAL FIREPLACE.

1,322,603.

Specification of Letters Patent. Patented Nov. 25, 1919.

Application filed August 21, 1917. Serial No. 187,454.

To all whom it may concern:

Be it known that I, WILLIAM F. NORMAN, a citizen of the United States, residing at Nevada, in the county of Vernon and State 5 of Missouri, have invented certain new and useful Improvements in Collapsible Metal Fireplaces, of which the following is a specification, reference being had therein to the accompanying drawing.

10 This invention relates to improvements in collapsible fire places, one object of the invention being the provision of a fire place which is especially adapted for use in conjunction with tents and the like, and is so 15 constructed as to be readily set up or knocked down, and so as to, when knocked down, occupy the smallest amount of space.

A further object of this invention is the provision of a collapsible fire place in which 20 the fire receiving member constitutes a steady support so that the rings or ornamental portion may be buttoned or connected to the flaps of the tents with the greater portion of the fire place exteriorly 25 of the tent, so there is no danger of setting fire thereto.

A still further object of this invention is the provision of a device of this character 30 which is simple, inexpensive and durable in construction and which is thoroughly efficient and practical in use.

In the accompanying drawings:

Figure 1 is a front elevation of the complete fire place.

35 Fig. 2 is a section taken on line 2—2 of Fig. 1.

Fig. 3 is a central vertical sectional view thereof.

Fig. 4 is a top plan view thereof.

40 Fig. 5 is a view in elevation of the two sections of the smoke pipe or flue detached.

Referring to the drawings, the numerals 10 and 11 constitute the wings of the present construction and as each one is constructed 45 similarly, the description of one will suffice for both. The inner edge of the wings 10 and 11, as at 12 is rolled so that the side walls 13 and 14 of the fire place may be hingedly connected by the coöperation of 50 the rolls 12 and 15, which are not only swinging connections but longitudinally slideable and nesting connections, so that each member is supported throughout its longitudinal length and is readily slid into or out 55 of position.

The rear edge of each of the members 13

and 14 is provided with the longitudinal roll 16 for engaging the similarly constructed roll 17 of the rear wall 18, the rear wall 18 being so constructed as to longitudinally 60 slide for disengagement from the side walls 13 and 14, when the present fire place is collapsed.

Each of the walls 13 and 14 is constructed with the corrugated inner face 13' which 65 terminates with the upper inclined edge 28 and the reduced end 29, the purpose of which will presently appear, there being located behind the corrugated walls of the respective members 13, 14, and 18, a layer 32 70 of heat insulating material, such as asbestos paper or the like.

The top 19 of the fire place, is provided with the upturned lip 20 for the reception of the groove 21 carried by the upper front 75 plate 22 of the fire place, there being a depending and guiding lip 23 formed upon the lower edge of such plate so as to assist in directing the smoke through the flue thimble 26 to the flue 27.

The upper extension of the wall 18 is provided with a flange 24 which provides a support for the rear edge of the top 19, so that its flange 25 will coöperate therewith to hold the parts assembled as shown in Fig. 3. 80

The flue 27, as shown in Fig. 5, is constructed of two longitudinal nesting sections *a* and *b*, which in turn are provided with the coöperating longitudinally disposed interlocking hooks or terminals *c* and *d*. 90 These may be any shape.

The top 30, of the fire box, is adapted to fit upon the inclined edges 28 of the corrugated faces 13' of the side walls 13 and 14, the right angled terminal 31 of the top 30 95 constituting a guide.

Carried by the wings 10 and 11, upon the rear face thereof, and also by the rear upper edge of the plate 22, are buttons 33 which are similar to the carriage top buttons, so 100 that the flaps or walls of the tent may be connected thereto and thus be held away from the hottest portion of the fire place, the plates 10, 11 and 22 being disposed within the tent while the greater portion of 105 the fire place is exteriorly thereof.

Connected to the front wall, near the lower portions of the wings 10 and 11, are the cleats 34, which provide supports for the rectangular bar 35, which in turn is provided with the uprights 36, which prevent the logs from rolling out into the tent. 110

The hinges 37 are connected to the rear of the bar 35 and thus hingedly connect the grate 38 thereto, so the same may assume the position as shown in Figs. 1, 2 and 3, or when not in use, may be folded upwardly and co-extensive with the members 36.

The rear wall 18 is provided with a longitudinal strip 39 which receives the rear end of the grate 38 as shown in Figs. 1 and 3, and thus supports the grate at this portion.

From the foregoing description, taken in connection with the drawings, it is evident that a fire place constructed according thereto is especially adapted for use in army camps and for sportsmen, and provides a ready means for attachment to the wall of a tent, as it is only necessary to split up the tent to accommodate the wings 10 and 11 and the plate 22, and provide button holes 20 therein for engaging the buttons 33.

What I claim as new is:

1. A collapsible fire place, including a sectional front member having an opening, two side walls hingedly connected to said member for projection from the rear side thereof, a rear wall constituting with the side walls the fire place, the same being slidably and hingedly connected to the rear edges of said side walls, a grate support attached to the rear walls, a hinged grate for fitting within the side walls and rear wall of the fire place, and a removable top wall for the fire place extending from the rear wall to a point adjacent the front of the fire place to provide a smoke outlet space adjacent thereto at the top of the fire place.

2. A collapsible fire place including a sectional front member having an opening, two side walls hingedly connected to said member for projection from the rear side thereof, a rear wall constituting with said side walls a fire place, said rear wall being slidably and hingedly connected to the rear edges of said side walls, a grate support attached to the rear wall, a hinged grate for fitting within the side walls and rear wall of the fire place, an inclined removable top wall for the fire place extending from the rear wall to a point adjacent the front of the fire place to provide a smoke outlet space adjacent thereto at the top of the fire place, and a cover removably fitting upon the upper edge of the rear wall and spaced from the top wall, said cover being also provided with a smoke outlet.

3. A collapsible fire place, including a sectional front member having an opening, two side walls hingedly connected to said member for projection from the rear side

thereof, a rear wall constituting with the side walls, the fire place, the same being slidably and hingedly connected to the rear edges of said side walls, a grate support attached to the rear wall, a hinged grate for fitting within the side walls and rear wall of the fire place, a removable top wall for the fire place extending from the rear wall to a point adjacent the front of the fire place to provide a smoke outlet space, a cover removably connected to the upper edge of the rear wall at a point above the top wall, said cover being provided with a smoke outlet, and a flue pipe for engaging said smoke outlet, composed of two longitudinal nesting sections, the meeting edges of which are provided with coöperating locking members.

4. A collapsible fire place, including a front composed of two wings and a connecting plate between the upper ends of the wings to provide an opening in the lower part of the front, the inner edge of each wing being rolled throughout its length while the opposite short edges of the connecting plate is rolled to receive the rolled edge of the wings to detachably connect the plate and wings together, and a fire place member detachably connected to the remaining rolled edges of both wings adjacent to the opening of the front.

5. A collapsible fire place, including a front composed of two wings and a connecting plate between the upper ends of the wings to provide an opening in the lower part of the front, the inner edge of each wing being rolled throughout its length while the opposite short edges of the connecting plate is rolled to receive the rolled edge of the wings to detachably connect the plate and wings together, a fire place member detachably connected to the remaining rolled edges of both wings adjacent to the opening of the front, said fire place including two side walls and a rear wall, a top for the fire place supported between the side and rear walls intermediate of the upper ends thereof and terminating at a point adjacent the front to provide a smoke space, a sheet of metal constituting the cover for the fire place fitting upon the upper edges of the side and rear walls and provided with a smoke outlet, a bar detachably connected to the wings for disposition transversely of the fire place, and a grate hingedly connected to the bar for projection within the fire place.

In testimony whereof I affix my signature.

WILLIAM F. NORMAN.
